UNITED STATES PATENT OFFICE.

LOUIS H. BRITTON, OF CLEVELAND, OHIO.

DESIGN FOR A FIRE-INDICATOR.

No. 38,446.

Specification for Design.

Patented Feb. 19, 1907.

Application filed January 2, 1907. Serial No. 350,551. Term of patent 14 years.

To all whom it may concern:

Be it known that I, LOUIS H. BRITTON, a citizen of the United States, residing at Cleveland, in the county of Cuyahoga, State of Ohio, have invented a new, original, and ornamental Design for a Fire-Indicator, of which the following is a specification, reference being had to the accompanying drawing, in which—

Figure 1 is a side elevation of a fire-indi-

cator, showing my new design; and Fig. 2 is a front view of the same

I claim—

The ornamental design for a fire-indicator as shown.

LOUIS H. BRITTON.
